APPARATUS FOR WRAPPING ARTICLES
WITH STRANDS

Samuel M. Martin and Oscar G. Nelson, Baltimore, Md., assignors to Western Electric Company, Incorporated, New York, N. Y., a corporation of New York

Application November 27, 1943, Serial No. 512,005

11 Claims. (CL 242—7)

This invention relates to apparatus for wrapping articles with strands and more particularly to apparatus for wrapping splices in electrical communication cords with textile strands.

In the manufacture of certain kinds of communication cords, the conductors of several individual cords are spliced together. The splices thus formed are each wrapped with an insulating material and the entire joint is wrapped with a strand to form a filler which serves as a base for an insulating composition applied thereover.

It is an object of this invention to provide new and improved apparatus for wrapping articles with strands.

One device embodying the invention comprises a chuck for holding an article to be wrapped, a holder for supply of wrapping cord, means to rotate the holder about an article held by said chuck to wrap a cord around the article, and means to move the chuck and the article held thereby relative to the holder for controlling the distribution of the cord upon the article.

A clear understanding of the invention may be obtained from the following detailed description of a specific embodiment of the invention, when read in conjunction with the appended drawings, in which

Fig. 1 is a front elevation of an apparatus embodying the invention;

Fig. 2 is a side elevation of the apparatus;

Fig. 3 is a sectional view taken along the line 3—3 in Fig. 1;

Fig. 4 is an enlarged, fragmentary, vertical sectional view of a portion of the apparatus shown in Fig. 3;

Fig. 5 is an enlarged sectional view taken along the line 5—5 in Fig. 4;

Fig. 6 is a vertical sectional view taken along the line 6—6 in Fig. 3;

Fig. 7 is an enlarged, fragmentary, perspective view of a portion of the apparatus;

Fig. 8 is a fragmentary side view of the apparatus;

Fig. 9 is a fragmentary sectional view taken along the line 9—9 in Fig. 8.

Fig. 10 is a fragmentary view, in partial section, taken along line 10—10 of Fig. 8;

Fig. 11 is a fragmentary perspective view of a portion of the apparatus, and

Fig. 12 is a fragmentary view of an article to be wrapped by the apparatus, with portions thereof broken away.

Referring now to the drawings, a standard 20 (Fig. 3) having a bearing 21 formed thereon is attached to a base plate 22 which is secured to

the top of a work table 25. A hollow shaft 26 (Fig. 4) fitting closely in bushings 27—27 positioned in grooves 29—29 formed in the bearing 21 is secured for rotation therein by annular plates 30 and 31 secured to the ends thereof by bolts 32—32 and 33—33, respectively. Washers 35—35 abutting against the bearing 21 and a sprocket 36 secured to the shaft 26 by a set screw 37 prevent relative longitudinal movement between the shaft 26 and the bearing 21. An arbor 39 also secured to the shaft 26 by the bolts 33—33 has a guide cap 40 threaded on the outer end thereof. The guide cap 40 has an aperture 41 formed centrally therein and has a smooth convex surface 42 formed thereon.

A hollow rod 45 (Fig. 3) having a keyway 46, a slot 47, and aligned apertures 49—49 formed therein is slidably secured by a key 50 in a bearing 51 bolted to the standard 20. A pin 53 is secured in the aligned apertures 49—49. The bearing 51 is positioned on the standard 20 in such a manner that the rod 45 is aligned with the axis of the shaft 26 into which one end of the rod projects. A sleeve 52 secured in the shaft 26 by a set screw 55 prevents excessive play between the rod 45 and the shaft 26.

One end of a hollow chuck 56 (Figs. 3 and 7) having longitudinal slots 57—57 formed in one end thereof is threaded into one end of the rod 45 and is secured in that position by a set screw 59. The slots 57—57 divide the end of the chuck in which they are formed into four resilient, wedge-like jaws 60—60. A sleeve 61 is slidably mounted within the arbor 39 and surrounds the chuck 56. The sleeve 61 is urged toward the right, as shown in Fig. 3, by a coil spring 62 engaging a shoulder 65 formed on the rod 45 and a flange 66 formed on the sleeve 61. A washer 67 on the sleeve 61 separates the flange 66 and a shoulder 69 formed on the arbor 39 when the sleeve 61 is in its extreme position to the right, as viewed in Fig. 3.

An arm 70 (Fig. 2) having a slot 71 formed in the upper end thereof is secured to a sleeve 72 rotatably mounted on a pin 75 projecting between arms 76—76 of a bracket 77 bolted to the work table 25. A second arm 79 having apertures 80—80 formed therein is also rigidly secured to the sleeve 72 and is adjustably connected by a pin 81 to a link 82. The other end of the link 82 is pivotally mounted to an arm 85 by a pin 86 which passes through one of a plurality of apertures 87—87 formed in the arm 85. The arm 85 is pivotally secured to the bracket 77 by a bolt 89 passing through apertures 84—84 formed

in the arms 88-89 and through a sleeve 80 secured to the arm 85. A tension spring 91 with one end thereof hooked over one of a plurality of pins 82-92 secured between the arms 76-78 and the other end thereof hooked through an aperture 95 formed in the arm 79 urges the arm 79 to the left, as viewed in Fig. 2. A pedal 96 rotatably mounted on the arm 85 by a bolt 97 serves to move the system of levers just described against the action of the spring 91.

A motor 98 of a conventional type is mounted on the top of a housing 99 and rotates a conventional drive 100 terminating in a shaft 101 upon which a sprocket 102 (Fig. 3) is secured in alignment with the sprocket 36. The sprocket 102 transmits power from the shaft 101 to the sprocket 36 by means of a chain 103. The sprocket 36 rotates the shaft 26, the arbor 39, and the plate 31, as well as a ball of cord 104 secured on the arbor by the guide cap 40. A brake shoe 105 pivotally mounted on a bolt 106 projecting from the plate 31 is pressed against the ball of cord 104 by a coil spring 107, thereby tending to prevent rotation of the ball of cord with respect to the arbor 39. A pair of discs 108-108 is slidably mounted on a pin 109 mounted on an arm 110 secured to the plate 31 and the discs are urged together by a spring 111. A guide roller 112 (Fig. 6) is also mounted on the plate 31.

A switch-operating pedal 113 (Fig. 2) is pivotally mounted by a bracket 115 bolted to a base 116 forming a part of the base of the work table 25. A rod 117 is pivotally connected to the pedal 113 by a bolt 119 secured in a bearing 120 welded to the end of the pedal 113. A spring 121 is attached at one end to the bolt 89 and is secured by means of an S-shaped hook 122 to a block 123. The block 123 is secured adjustably to the rod 117 by a set screw 126, and the rod is urged upwardly, as viewed in Fig. 2, by the action of the spring 121.

A turnbuckle 127 (Fig. 2) adjustably joins the rod 117 to a second rod 129 which is attached to a lever 130. The lever 130 actuates a conventional switch 131 controlling the operation of the motor 98. When the lever 130 is urged upwardly, as shown in Fig. 2, by the action of the spring 121, the switch 131 is in the "off" position. When the left end of the pedal 113 is pressed downwardly, as viewed in Fig. 2, the switch 131 will be closed to start the operation of the motor 98.

A housing 132 (Fig. 1) having an opening 135 formed therein concentric with the chuck 56 is provided to enclose the chuck and the ball of cord. A door 136 (Fig. 11) forming a part of the housing 132 is rigidly secured to a rod 137 (Fig. 8) rotatably mounted in bearings 138-139 bolted to the housing 132 and in a bearing 140 bolted to the base plate 22.

A lever 141 attached by set screws 142-142 to the rod 137 is pivotally attached to one end of a bar 145 (Figs. 9 and 10). The other end of the bar 145 passes through an aperture 146 formed in a guide 147 secured to the work table 25 and is thrust beneath a dog 149 adjustably secured by set screws 150-150 to the rod 129 when the door 136 is in its open position, as shown in dotted lines in Fig. 9. When the bar 145 is thrust under the dog 149, the rod 129 will be prevented from being drawn downwardly to close the switch 131 and thus the apparatus cannot be operated while the door 136 to the guard housing 132 is open. Consequently, the risk of injuries to an operator of the apparatus is avoided. When the door 136 is closed, the end of the bar 145 will be retracted

from beneath the dog 149 and the switch 131 may be closed at the will of the operator. The door 136 may be latched in a closed position by a conventional latch 151 (Fig. 1).

- 5 An arm 152 (Fig. 3) pivotally secured by a pin 155 to a bracket 156 bolted to the base plate 22 is biased in a clockwise direction, as viewed in Fig. 3, by springs 157-157 coiled around the pin 155, and secured to the arm by screws 158-158. 10 A stop 159 bolted to the arm 152 limits the clockwise rotation of the arm by striking the top of the work table 25. An L-shaped rod 160 passing through an aperture 161 formed in a projection 162 (Fig. 1) formed on the arm 152 is urged downwardly by a compression spring 165 mounted thereon which presses against the projection 162 and against a washer 166 secured on the rod by a collar 167 attached to the rod by a set screw 168 (Fig. 3). A plate 170 welded to the rod 160 cooperates with the projection 162 to form a clamp in which two arms 171-171 of a Y-type cord 172 to be operated on are held by the downward pressure of the spring 165 acting on the rod 160.

15 In the operation of the above described embodiment of the invention, a stem 175 (Fig. 4) of the Y-type cord 172 is inserted between the jaws 60-60 of the chuck 56 so that insulated splices 176-176 of conductors 177-177 of the stem 175 and the arms 171-171 of the Y-type cord 172 are just outside of the cap 40, as shown in Fig. 4. The pedal 96 is then pressed downwardly to pivot the arm 85 clockwise, as viewed in Fig. 2, which in turn through the link 82 rotates the arms 79 and 70 counterclockwise against the action of the spring 91. The arm 70 acting against the pin 53 moves the hollow rod 45 to the left, as shown in Fig. 3, and advances the chuck 56 to a position where the jaws 60-60 bear against the beveled end of the sleeve 61 which forces the jaws radially inwardly to firmly grip the stem 175 therebetween.

20 At this point in the operation, the L-shaped rod 160 and the plate 170 attached thereto are raised against the action of the spring 165 and the arms 171-171 of the cord 172 are inserted between the projection 162 and the plate 170. The cord 172 then is drawn taut, and the rod 160 is released whereby the arms 171-171 are securely clamped between the projection 162 and the plate 170.

25 The end of a strand 173 forming the ball of cord 104 is drawn over the pin 112, between the discs 108-108, and over the convex surface 42. The end of the strand then is wound around the cord 172 and is carried along the arms 171-171.

30 The pedal 113 is pressed to close the switch 131 thereby starting the motor 98, which rotates shaft 101 and the sprocket 102 carried thereby. The sprocket 102 drives the chain 103 which rotates the sprocket 36, thereby rotating the shaft 26, the arbor 31 and the ball of cord 104 around the chuck 56 and the cord 172 held by the chuck.

35 As the arbor 31 is rotated around the cord 172, the strand 173 is wrapped around the cord and is placed under tension by the braking action of the spring pressed discs 108-108 and the brake shoe 105 which presses against the periphery of the cord 104. The brake shoe 105 tends to prevent any rotation of the ball of cord 104 with respect to the arbor 31, thereby tending to keep the strand 173 under tension as the strand is withdrawn from the ball.

40 As the strand 173 is being wound around the

cord 172, the pedal 96 is pressed farther downwardly to move the chuck 56 and the cord 172 to the left relative to the cap 40, as seen in Fig. 4, and consequently the strand will be guided by the cap to the bared portions of the conductors 177—177 being drawn past the convex surface 42 of the cap. After the cord 172 has been moved a sufficient distance for all of the bared portions of the conductors 177—177 to be wrapped by the strand 173, the pressure on the pedal 96 may be lessened to permit the spring 91 to move the chuck and the cord 172 held thereby slowly toward the right, as viewed in Fig. 4, whereupon another layer of the strand will be wrapped around the cord 172. The springs 157—157 will rotate the arm 152 away from the arbor at the same time and thereby draw the arms 171—171 of the cord 172 away from the arbor. Thus, the cord 172 may be reciprocated back and forth past the convex surface 42 and the wrappings of the strand 173 applied thereon may be built up to any desired thickness. When the chuck 56 is moved to the right, as viewed in Fig. 4, it is not moved much beyond the position shown in Fig. 4, otherwise the jaws 60—60 would slide out of the sleeve 61 and release the cord 172.

After the strand 173 has been wrapped to the desired thickness upon the cord 172, the pedal 118 is released to open the switch 131 and stop the motor 98. The strand 173 is severed and the severed end is tied to the end thereof initially layed along the arms 171—171 to prevent unwinding of the portion of the strand wrapped around the cord. The pedal 96 is then completely released to permit the jaws 60—60 to spring open, thus releasing the stem 175 of the cord 172.

When the ball of cord 104 is exhausted, a similar one may be substituted therefor by removing the cap 40 from the arbor 39, sliding the new ball on the arbor, and rethreading the cap thereon. When the strand of the substituted ball of cord is to be threaded between the discs 108—108, the latch 151 is opened and the door 136 moved to the dotted line position shown in Fig. 9 to facilitate the step of threading. While the door 136 is in such a position, the bar 148 prevents any accidental starting of the motor 98, as pointed out hereinabove.

The length of the portion of the cord to which the strand is applied may be varied by attaching the ends of the link 82 to the arms 70 and 85 at different ones of the apertures 80—80 and 87—87. This causes the distance of travel of the chuck for a given motion of the foot pedal 96 to be varied.

What is claimed is:

1. In a strand applying apparatus, means for clamping an elongated article, means to actuate said clamping means, a strand supplying means, means for rotating the strand supplying means about both the first mentioned means and an article held thereby to wrap a strand about a portion of the article, and means for moving the first mentioned means and the article held thereby relative to the strand supplying means to distribute the windings of the strand on the article.

2. In a strand applying apparatus, means for clamping one end of an elongated article, means for actuating the first mentioned means to securely grip the end of such an article, a strand supplying means, means for rotating the strand supplying means about an article held by the first mentioned means to wind a strand about

a predetermined portion of the article, means for moving the article relative to the strand supplying means, and means for tensioning the article.

3. In a strand supplying apparatus, a chuck having jaws formed thereon for clamping the end of an article, means for urging the jaws together to clamp the end of an article therebetween, a cylindrical holder for carrying a strand supply positioned around said chuck in concentric relationship thereto, means for rotating said holder around both the chuck and an article held by the chuck to wind a strand around a predetermined portion of the article, and means for moving the chuck and article held thereby to wind the strand around a different portion of the article.

4. In a strand applying apparatus, means for holding an elongated article, a strand supplier, means for rotating the strand supplier around an article held by the first mentioned means to wind a strand thereon, means for reciprocating the first mentioned means relative to the strand supplier to distribute the turns of the strand along the article, and means for tensioning the article during such reciprocation.

5. In a strand applying apparatus, a chuck, a rotatable strand supplying means, means for rotating the strand supplying means around an article held by said chuck to wrap a strand around the article, means for reciprocating the chuck and the article held thereby relative to the strand supplying means, and means for tensioning the article during such reciprocation.

6. In a strand applying apparatus, a hollow arbor, means for retaining a ball of cord upon the arbor, a chuck positioned in the arbor for clamping one end of an article, means for rotating the arbor around the chuck to wind a cord around a predetermined portion of an article held by the chuck, and means for reciprocating the chuck to distribute the windings of the cord upon the article.

7. In a strand applying apparatus, a chuck having wedge-like jaws formed thereon, a sleeve positioned around the chuck, a spring for urging the sleeve over the wedge-like jaws to close the jaws upon an elongated article positioned in the chuck, means for clamping an elongated article held by said jaws, means for resiliently supporting the clamping means to tension the article, a strand supplying arbor mounted concentrically with the chuck, means for rotating the arbor around the article to wind a strand around a predetermined portion of the article, and means for reciprocating the chuck with respect to the arbor to distribute the winding of the strand upon the article.

8. In a strand applying apparatus, a chuck having a plurality of resilient, wedge-like jaws formed thereon, a sleeve slidably mounted on the chuck, means for urging the sleeve over the jaws to clamp an article positioned between the jaws, a strand supplying arbor, means for rotating the arbor around the article, means for moving the chuck and the article in one direction relative to the arbor, and means for urging the chuck in the opposite direction.

9. In a strand applying apparatus, a chuck having a plurality of resilient, wedge-like jaws formed thereon, a sleeve slidably mounted on the chuck, a spring for urging the sleeve over the jaws to clamp an elongated article therebetween, a pivoted lever adjacent to the chuck, means for urging the lever away from the chuck,

means for securing a portion of an article clamped by the jaws upon the end of the lever, a strand supplying arbor, means for rotating the arbor around the chuck to wrap a strand around the article, positively driven means for moving the chuck in one direction relative to the arbor, and resilient means for urging the chuck in the opposite direction.

10. In a strand applying apparatus, an elongated member, means associated with the member for securing a cord thereto, an arbor for wrapping a strand around a cord secured by said means, a system of levers for moving the member a predetermined distance with respect to the arbor, and means for adjusting said system 15 of levers to vary said predetermined distance.

11. In a strand applying apparatus, a rotatable arbor for holding a strand supply, an elongated member mounted concentrically with said arbor, means for securing a cord to said member, means for rotating said arbor with respect to the member to wrap a strand drawn from the supply around a cord secured to the member, a linkage system for moving said member a predetermined distance relative to said arbor to distribute the strand upon the cord, and means for adjusting the linkage system to vary said predetermined distance.

SAMUEL M. MARTIN.
OSCAR G. NELSON.
